UNITED STATES PATENT OFFICE.

MICHAEL FRANCIS McGOWAN, OF BREMERTON, WASHINGTON.

GAME APPARATUS.

1,274,178.

Specification of Letters Patent. Patented July 30, 1918.

Application filed February 6, 1918. Serial No. 215,609.

To all whom it may concern:

Be it known that I, MICHAEL FRANCIS McGOWAN, a citizen of the United States, residing at Bremerton, in the county of Kitsap, State of Washington, have invented a new and useful Game Apparatus; and I do hereby declare the following to be a full, clear, and exact description of the invention, such as will enable others skilled in the art to which it appertains to make and use the same.

This invention relates to an improved game apparatus, and one of the objects of the invention is to provide a simple, efficient and practical apparatus of this kind, which is inexpensive in construction and may be sold at a reasonable profit.

A further object of the invention is to provide a game apparatus, which is scientific in the mode of play, and will give the players a great deal of amusement and pleasure.

A further object of the invention is to provide an improved game apparatus, so constructed that the various parts may be easily and quickly disassembled, so as to be packed in a small compass when not in use.

In practical fields the details of construction may necessitate alterations falling within the scope of what is claimed.

The invention comprises further features and combination of parts as hereinafter set forth, shown in the drawings and claimed.

In the drawings:

Figure 1 is a plan view of the improved game apparatus constructed in accordance with the invention.

Fig. 2 is a view in side elevation.

Fig. 3 is a longitudinal sectional view on line 3—3 of Fig. 1.

Referring more especially to the drawings, 1 designates the frame of the game board of the apparatus. This frame may be constructed of any suitable material, preferably sheet metal or the like, and the frame comprises the bottom 2 and a marginal flange 3, which consists of the end pieces 4 and 5 and the longitudinal side pieces 6 and 7, and the upper edge of the flange is formed in a bead or roll 8, said bead or roll having an interior wire 9, for stiffening or reinforcing the sides and ends of the frame. The lower edge of the flange also has a bead 11 provided with an interior stiffening wire 12, to further reinforce the structure. One end portion of the bottom 2 is bent as at 13

and 14, to provide the downwardly overset portion 15. This portion 15 is provided with a pair of upstanding lugs 16, which are bolted as at 17 to the rear end piece 4 of the marginal flange. The bottom 2 at its side portions is provided with downwardly extending ears 18, which are secured by bolts 19 to the longitudinal side pieces 6 and 7 of said frame. Adjacent where the bottom 2 extends downwardly a suitable sheet metal partition 20 is arranged. The ends of this partition have ears 21 secured by bolts 22 to the longitudinal side pieces 6 and 7. By providing the offset portion 15 and by means of the partition 20, the frame is divided into the compartments 23 and 24. The space 24 is utilized for containing the balls to be actuated by the master-ball. The space 23 is sub-divided by the partition 25, the lateral ears or lugs 26 of which are secured by bolts 27 to the end piece 4 and the partition 20. The partition 20 is spaced upwardly from the bottom 2 and extending transversely of the frame near the lower edge of said partition is a rod 28, on which the roll or beaded edge 29 of the oscillatory member 30 is pivoted. This oscillatory member 30 constitutes means to normally close the space between the lower edge of the partition 20 and the bend 13 of the bottom 2. A suitable leaf spring 31 is secured at 32 to the partition 20, and the free end of the spring 33 bears against the oscillatory member 30, in order to hold the member 30 normally closed. A spring arm 34 is secured at 35 to the member 30. The bottom 2 at a point indicated by the numeral 36 merges into a slightly inclined part 37, so that the master or actuating ball 38 will remain in contact with the member 30, when the ball 38 is once set. A shaft 39 is mounted in bearings 40 and 41 in the partition 25 and the longitudinal side piece 7 respectively. Near the outer end of the shaft 39 a ratchet wheel 42 is mounted and on the outer extremity of the shaft 39 a knob 43 is secured in any suitable manner. A spring pawl 44 secured at 45 to the longitudinal side piece 7 of the frame engages the ratchet 42 to prevent retrograde movement of the shaft 39, which rotates normally in the direction of the arrow a. A suitable sleeve 46 is secured by a set screw 47 on the shaft 39, and this sleeve is provided with radial arms 48, which are designed to pass by the spring arm 34, when the shaft 39 is rotated, so as

to trip the oscillatory member 30, which flies back into position under the tension of the spring 33, and actuates the master ball 38 in the direction of the arrow *b*. A bottom 5 section 49 is provided, the same having ears 50 at its side edges secured by bolts 51 to the forward parts of the side pieces of the frame. Hinged at 52 to the forward edge of the bottom section 2 is a trough 53, which 10 is provided with a plurality of compartments 54, 55, 56, 57 and 58. The center compartment or pocket 54 is designed to receive the "shilo" ball and when such ball enters the pocket or compartment 54, the 15 player firing or shooting said ball in the pocket wins the game. The other pockets toward the opposite sides are numbered respectively from 20, 15, 10 and 5, the center pocket 54 being numbered 30, and the balls 20 entering these pockets count for the player according to the numbers respectively named. If the shilo ball enters any one of the pockets other than the pocket 54, the shilo ball counts the same as any other of 25 the balls designated by the numeral 59. The shilo ball is designated by the numeral 60. The balls 59 and the shilo ball 60 are designed to be racked in a triangular contour by means of the triangular frame 61, on the 30 forward end of the space 24 of the game board of the apparatus. If any of the balls 59 enter the shilo pocket 54 the player counts 30, or according to the numbers on the shilo pockets. The counting numbers of 35 the pockets are printed upside down, so that the reflection of the numbers in the mirror 62 may be correctly read by the players at the other end of the game apparatus. The mirror 62 is supported in a frame 63, which 40 is pivoted at 64 between the forward ends of the side pieces of the frame. When the game apparatus is out of use, the mirror may be tilted downwardly on the trough 53, as indicated in dotted lines in Fig. 2. The 45 forward end of the frame has a transverse piece 65, provided with ears 66, which is secured by bolts 67 to the forward parts of the side pieces of the frame. A closure 68 is pivotally secured as at 69 to the cross 50 piece 65, and said closure may be closed as shown in Fig. 2 when the mirror frame is moved to its dotted line position. The ends of the trough 53 have laterally extending pins 69 which pass through the segment 55 slots 70 of the side pieces of the frame, so as to guide the trough when tilted upwardly, so as to discharge the balls from the pockets or compartments on the bottom 2 of the game board. The bottom 2 of the game 60 apparatus and the interior of the trough is lined with some suitable material such as felt or the like 71 and 72, so as to deaden the sound incident to the balls rolling on said surfaces. Suitable wickets 73 rise upwardly from the forward end of the bottom 65

2 and are spaced according to the divisions between the pockets or compartments, that is according to the width of the pockets. A transverse metal strip 74 is riveted to the upper ends of the wickets and the longitudinal edges of this strip 74 have flanges 75 between which the arch strip 76 engages, thereby reinforcing the strip 74, which engages between the side pieces of the frame, hence preventing lateral movement of the 75 wickets. A triangular shaped frame 77 has its ears 78 secured by bolts 79 to the side piece 7 of the frame, and this frame 77 is designed to receive the racking frame 61, which is used for racking the balls. The 80 side piece 7 of the frame has a cutaway portion 80, to permit the insertion of the racking frame 61. The bottom of the rack receiving frame has a cutaway part 81, to permit the hand of the player to grasp the rack, 85 for the purpose of removing the same, when desired to rack the balls. The master ball 38 is of a larger diameter than the balls 59, so as to be unable to enter between the wickets and into the pockets. The inner faces 90 of the side pieces 6 and 7 are covered by means of suitable felt 82, and the forward face of the oscillatory member is also covered with felt 83, for the purpose of deadening the sound. 95

In playing this improved game, the balls 59 and the shilo ball are first stacked by means of the rack 61. The rack is removed and placed in its pocket 77. The first player then places the master ball 38 in the position that may be desired to secure the best aim at the stack of balls forward of the game-board. The player then rotates the knob 43 which turns the shaft 39 sufficiently to trip the spring arm 34, tilting the oscillating member 30 and when it returns under the action of the spring 33, the master ball 38 will be fired or shot or thrown toward the stack of balls, which will become scattered. The various balls will be tossed about on the game-board, some passing through the wickets and into the pockets or compartments, and others will remain in various positions on the board. The player then sets the master ball 38 according to the aim desired and again fires or shoots the same. The player continues these operations until all of the balls 59 and 60 are cleared from the game-board. The shilo ball 60 is of a different color than the balls 59, for instance, black, and should this ball enter the pocket or compartment 54 the player wins the game. However, should the shilo ball enter any other pocket or compartment other than 54 it counts according to the 100 number of the pocket in which it enters, the same as any of the balls 59. Should any of the balls 59 enter the shilo pocket it counts according to the number 30 over the pocket. Should any one of the balls 59 and 60 locate 105 110 115 120 125 130

near the oscillating member 30, it is placed on the spot 60^a, and other balls becoming located near the member 30 are placed to the rear of the first ball on the spot in alignment therewith.

The invention having been set forth, what is claimed as new and useful is:—

1. In a game apparatus, a game-board on which at one end a plurality of counting balls may be racked, a master ball to be placed at the other end of the game-board, an oscillatory master ball firing member at one end of the board, a plurality of pockets extending transversely of the board at the other end having numbers of various denominations employed in counting the game according to the balls entering the pockets, and a reflecting member in which the numbers of the pockets are reflected.
2. In a game apparatus, a game-board having a trough hingedly united at one end, said trough having a plurality of pockets provided with counting numbers of various denominations, and a spring-tensioned master ball firing member pivotally united at the other end of the board for shooting a master ball toward a stack of balls in advance of the pockets.
3. In a game apparatus, a game-board having a trough hingedly united at one end, said trough having a plurality of pockets provided with counting numbers of various denominations, a spring-tensioned master ball firing member pivotally united at the other end of the board for shooting a master ball toward a stack of balls in advance of the pockets, and means for actuating said firing member.
4. In a game apparatus, a game-board, having a trough hingedly united at one end, said trough having a plurality of pockets provided with counting members of various denominations, a spring-tensioned master ball firing member pivotally united at the other end of the board for shooting a master ball toward a stack of balls in advance of the pockets, means for actuating said firing member, and a series of transversely arranged wickets in front of the pockets of the trough.
5. In a game apparatus, a game-board having a trough hingedly united at one end, said trough having a plurality of pockets

provided with counting numbers of various denominations, a spring-tensioned master ball firing member pivotally united at the other end of the board for shooting a master ball toward a stack of balls in advance of the pockets, and a series of transversely arranged wickets in front of the pockets of the trough.

6. In a game apparatus, a game-board, a trough member extending transversely of the board at one end and having a plurality of pockets provided with counting numbers of various denominations, means for mounting said member whereby the same may be tilted to discharge the balls back upon the game board.

7. In a game apparatus, a game-board, a trough member extending transversely of the board at one end and having a plurality of pockets provided with counting numbers of various denominations, means for mounting said member whereby the same may be tilted to discharge the balls back upon the game board, and an oscillatory master ball firing member at the other end of the game-board for shooting a master ball at a plurality of balls racked in advance of said pockets.

8. In a game apparatus, a game-board, a trough member extending transversely of the board at one end and having a plurality of pockets provided with counting numbers of various denominations, means for mounting said member whereby the same may be tilted to discharge the balls back upon the game board, an oscillatory master ball firing member at the other end of the game-board for shooting a master ball at a plurality of balls racked in advance of said pockets, means for actuating said firing member, a series of wickets arranged transversely of the game-board in advance of the pockets, and a mirror in the rear of the pockets in which the counting numbers are reflected, said game-board having means to receive a ball rack when not in use.

In testimony whereof I have signed my name to this specification in the presence of two subscribing witnesses.

MICHAEL FRANCIS McGOWAN.
